UNITED STATES PATENT OFFICE.

SAMUEL FERDINAND WOLFF, OF MORRIS, MINNESOTA.

CHOKE-UP ALARM.

SPECIFICATION forming part of Letters Patent No. 393,412, dated November 27, 1888.

Application filed March 20, 1888. Serial No. 267,872. (No model.)

To all whom it may concern:

Be it known that I, SAMUEL FERDINAND WOLFF, a citizen of the United States, residing at Morris, in the county of Stevens and 5 State of Minnesota, have invented a new and useful Improvement in Choke-Up Alarms, of which the following is a specification.

My invention relates to an improvement in choke-up alarms for mill-conveyers; and it 10 consists in the peculiar construction and combination of devices, that will be more fully set forth hereinafter, and particularly pointed out in the claims.

In the accompanying drawings, Figure 1 is 15 a perspective view of a portion of a mill-conveyer, showing my improved choke-up alarm connected thereto. Fig. 2 is a vertical longitudinal sectional view of my improved burglar-alarm taken on the line xx of Fig. 4. Fig. 20 3 is a similar view taken on the line yy of Fig. 4. Fig. 4 is a vertical transverse sectional view of the same.

a represents the trough of a mill-conveyer of the ordinary construction. 25 b represents the usual worm arranged in the lower side thereof, and c represents the usual spout, which communicates with one end of the conveyer and extends downward therefrom.

30 It frequently happens in mills that this spout becomes choked up when the mill is in operation, and in order to prevent flour from accumulating in the conveyer to an undue extent the conveyer is provided on one side near its discharge end with an outwardly-opening door, d , which is hinged at its upper side, and is adapted to close by its own gravity. This door opens automatically when the flour accumulates in the conveyer and the spout becomes 35 choked and permits the surplus flour to spill onto the floor.

The object of my invention is to provide an apparatus which is adapted to be connected to this door and operated by the same, so as 40 to sound an alarm when the spout chokes.

A represents an inclosing-case of suitable size and shape, which is supported in any suitable manner at a convenient distance from the discharge end of the conveyer. In this case is 45 journaled a revoluble shaft, B , which has one projecting end squared, and thereby adapted

to receive a key or handle, by means of which the shaft may be turned.

Rigidly secured to the said shaft is a drum, C , to which is connected one end of a cord, D . 55 This cord passes over a guiding sheave, E , and to its pendent end is attached a weight, F .

G represents a ratchet-wheel of suitable size, which is provided at its center with a collar or sleeve, H , that forms its hub and slips on 60 the shaft B and is made rigid thereto, so that the ratchet-wheel will rotate with the shaft.

Loosely journaled on the sleeve or collar H , and arranged between the drum C and ratchet-wheel G , is a large spur-wheel, I . Pivoted to 65 this spur-wheel is a spring-actuated pawl, K , which engages the ratchet-wheel G , and thereby permits the spur-wheel to rotate in one direction independently of the shaft B and of the wheel G and drum C , but causes said spur-wheel to rotate with the shaft and the wheel G and drum C when the shaft is rotated in 70 the opposite direction.

L represents a shaft, which is journaled in the sides of case A at a suitable distance above 75 the shaft B . This shaft L is provided with a rigid pinion, M , which meshes with spur-wheel I , has a disk, N , provided with a series of tappet pins, O , which project from one side thereof and are arranged at suitable regular distances 80 apart, and said shaft L is further provided with a pinion, P .

R represents an escapement-wheel, which is loose on the shaft B and meshes with pinion P .

S represents a pallet-escapement, which engages the escapement teeth on the lower side of wheel R , and is rigidly secured to a supporting rock shaft, T , that has its bearings in the case A in the usual manner. Rigidly secured to the said shaft, and depending therefrom, is a pendulum-rod, U , of suitable length, to the lower end of which is attached a bob or weight, V . 90

On the upper side of the case A , and supported on a suitable standard that projects 95 therefrom, is a gong, W .

X represents a rock-shaft, which is journaled in the sides of case A , and from one side of said rock-shaft projects a tappet-arm, Y , of suitable length, which tappet-arm is adapted 100 to be engaged successively by the tappet-pins O of disk N , when the latter rotates with shaft

L. A stop-pin, Z, engages the under side of said tappet-arm when the same is at the lower limit of its movement and prevents said arm from dropping out of the path of tappet-pins O.

A' represents a vibratory arm, which projects upward from rock-shaft X, extends through a slot or opening, B', in the top of case A, and has a hammer, C', attached to its upper end, which hammer is adapted to strike the gong.

D' represents a lever, which is arranged substantially in a vertical position, and is pivoted on a shaft or spindle, E'. The upper end 15 of this lever projects through an opening, F', in the top of the case, and the lower end thereof is bent at right angles and provided with a point, G', which engages one of the teeth of the pinion M, and is thereby adapted to prevent 20 said pinion and the shaft L, to which it is attached, from rotating. A spring, H', is coiled on the shaft or spindle E', has one end rigidly secured thereto, and has its opposite extremity 25 engaging the lever D', the function of the said spring being to normally keep the point of said lever in engagement with the pinion M.

I' represents a detent arm, which is resilient, is pivoted on the upper side of case A, as at K', has a set-screw, L', at its outer end, and 30 has its opposite extremity bifurcated and engaged with the lever D'. This detent-arm bears against the lever D' with a force sufficient to prevent said lever from becoming accidentally disengaged from pinion M, and the 35 degree of force with which said detent arm or spring bears against said lever may be regulated by turning said adjusting-screw L', as may be very readily understood.

M' represents a cord or chain, which is attached to the upper end of lever D', passes under a sheave, N', on one side of the conveyer, and has its upper end secured to the lower or free edge of the hinged door d.

The operation of my invention is as follows: 45 On applying a key to the shaft B and turning the same in the direction indicated by the arrow in Fig. 2 the drum C and ratchet-wheel G rotate with the shaft, and thereby wind up the cord to which the weight is attached. 50 While the shaft is turning in this direction the pawl K slips idly on the ratchet-wheel, thus permitting the wheel I and the rest of the alarm mechanism to remain idle. As soon as the spout e becomes choked when the mill is 55 in operation the flour accumulates in the conveyer, as before described, and forces the door d open. As said door opens, it draws upon the cord or chain M', and thereby trips the lever D' and disengages the same from the 60 pinion M, thus leaving the pinion and the mechanism of the alarm apparatus free to ro-

tate. The pressure exerted by the weight F and cord D on the drum causes the latter to revolve in the opposite direction to that indicated in Fig. 2, and carry the spur-wheel I with it, by reason of the pawl being in engagement with the ratchet-wheel. The rotary motion of wheel I imparts accelerated rotary motion to shaft L by reason of pinion M, and said shaft L causes the rigid disk N and pinion P to rotate therewith. As the disk rotates, its tappet-pins successively engage the tappet-arm of rock-shaft X, thereby imparting vibratory motion to the spring rod or arm A', and causes the hammer attached to said rod to strike 75 against the gong and sound an alarm, as will be very readily understood. The pinion P meshes with the escapement-wheel, and the latter, by reason of the pallet, causes the pendulum to oscillate, and the pendulum regulates 80 the speed of the alarm mechanism and prevents the same from running too fast. As soon as the spout has been cleared and the door d closes, so as to release the lever D', the spring arm or detent I' forces said lever back 85 into engagement with the pinion M, and thereby arrests the operation of the alarm.

Having thus described my invention, I claim—

1. An alarm apparatus having the detent-lever D', the pivoted spring-arm I', engaging said lever, for the purpose set forth, and the adjusting-screw L', to regulate the pressure of the spring-arm against the lever, in combination with the conveyer having the door connected to the lever D', substantially as described.

2. The combination of the shaft B, the drum or ratchet-wheel rigid therewith, the weighted cord attached to the drum, the wheel I, loose on shaft B and having the spring-pawl engaging the ratchet-wheel, the shaft L, having pinion M, engaging wheel I, disk N, attached to said shaft L and having tappet-pins O, the pinion P, secured to shaft L, escapement-wheel R, loose on shaft B and meshing with pinion P, the pallet engaging the escapement-wheel and having the pendulum, for the purpose set forth, the vibrating hammer having the arm Y, engaged and operated by the tappet-pins O, the spring-pressed lever D', engaging the pinion M, and the conveyer having the door connected to lever D', substantially as described.

In testimony that I claim the foregoing as my own I have hereto affixed my signature in presence of two witnesses.

SAMUEL FERDINAND WOLFF.
